UNITED STATES PATENT OFFICE.

WILLIAM S. HARRIS, OF TRENTON, NEW JERSEY.

IMPROVEMENT IN PORTABLE CRADLES.

Specification forming part of Letters Patent No. **146,069**, dated December 30, 1873; application filed November 8, 1873.

To all whom it may concern:

Be it known that I, W. S. HARRIS, of Trenton, in the county of Mercer and State of New Jersey, have invented certain new and useful Improvements in Portable Cradles; and I do hereby declare the following to be a full, clear, and exact description of the invention, such as will enable others skilled in the art to which it pertains to make and use it, reference being had to the accompanying drawings, which form part of this specification, in which—

Figure 1 is an under-side plan view of my invention. Fig. 2 is a vertical transverse section. Fig. 3 is a vertical sectional view, showing part of cradle folded.

My invention has for its object to provide a portable cradle, designed principally for the use of travelers. The nature of the invention consists in the peculiar construction and combination of parts, as hereinafter fully described.

The part of the cradle which corresponds in purpose with the mattress and sustaining-slats usually employed consists of a rectangular hammock or sack, of suitable textile material. This hammock is sustained upon a wooden frame, which is pivoted at each end upon A-shaped legs, said frame and legs being provided with hinges, so that they can be compactly folded, for convenient transportation, in a trunk or traveling-bag. The supporting-frame, when extended, is held in position by an encircling band, which may be ornamented, so as to give the cradle a finished and elegant appearance.

Referring to the accompanying drawing, A is a hammock or sack, of rectangular form, sustained in the frame B by means of rods *a a* passing through the side rails *B' B'*, and through pockets or loops on the hammock, and by the clamps *a¹ a¹*, engaging, as shown, with said side rails. The frame B is of the usual rectangular shape, jointed at its middle, as shown at *b*, and having hinged head and foot boards *B²*. It is also hinged at each of its four corners, as shown at *b¹ b²*. C C are the legs, hinged at their apexes *c c*, and affording bearings for the pins or journals *a²* in the end pieces of the frame B. By means of this pivotal arrangement, the desired rocking mo-

tion is obtained. D is a band, which holds the frame B firmly in its rectangular position when so adjusted, and may be made to subserve the purpose of ornament. The band D is held in position upon the frame B by means of hooks *d d*. E E are cords proceeding from the corners of the frame B to opposite corners of the hammock A, which latter is thereby compelled to accompany the former in its vibratory motion. The ends of the cords E E are provided with hooks *e e* to facilitate their attachment to the hammock.

The above is a description of the cradle arranged ready for occupancy.

In order to pack the cradle for transportation, the band D is first removed, the cords E unhooked, the rods *a a* withdrawn, the hammock A taken out of the frame, and the latter lifted off the legs C C. The frame B is then doubled up until the head and foot boards come together. The side rails are then folded over upon said head and foot boards, one side rail resting upon the other, which it is enabled to do by reason of the peculiar construction of the hinges *b²*, which are bent in such manner as to bring their joints on the same plane with the upper surface of the other rail, *B'*, when folded; or, in other words, and as shown in Fig. 1, the hinges *b²* have their joints a distance from the corner of the frame B equal to the thickness of the side rails. The head and foot boards are then folded up against the side of the rails *B'*, and the folded legs C placed between—one pair of said legs above and one below. The folded hammock and encircling band D, together with the rods, may then be added, and the several parts tied by the cords E E, the whole device thus packed requiring but a small amount of space in a trunk.

What I claim as my invention is—

1. The combination, with a portable cradle, having the side rails hinged at their middle parts to fold vertically, and at their ends to fold laterally, as described and shown, of the hinges *b²*, having their pintles located sufficiently forward of the corner-posts of the cradle, and of the pintles of hinges *b¹*, to allow the side rails to overlap parallel to each other, as specified.

2. The A-shaped legs C, hinged or jointed at their apexes, and affording pivotal bearings for the frame B, substantially as shown and described.

3. In combination with the rocking frame B and hammock A, the cords E, substantially as shown and described.

In testimony that I claim the foregoing I have hereunto set my hand this 3d day of November, 1873.

WILLIAM S. HARRIS.
